UNITED STATES PATENT OFFICE.

ARTHUR EMETT, OF BIRMINGHAM, ENGLAND.

SOUND-DAMPING MECHANISM.

Application filed February 10, 1922. Serial No. 535,535.

To all whom it may concern:

Be it known that I, ARTHUR EMETT, subject of the King of Great Britain, residing at 24 Tennyson Road, Small Heath, Birmingham, England, manufacturer, have invented certain new and useful Improvements in Sound-Damping Mechanism, of which the following is a specification.

The invention provides the hereinafter described improvements in or connected with sound reproducing instruments such as gramophones.

According to the invention an air sack is used within a tubular passage beyond the sound box to be hand operated for controlling the effective size of the passage to change the volume and mellow ness of the tone of the instrument at the will of the hearer. Said air sack is preferably an inflatable one normally contracted in the passage and inflated to reduce the effective area of said passage, but it may be an air sack normally inflated and capable of deflation for the purpose of controlling the effective size aforesaid. Said air sack is of india-rubber or other non-metallic material, or substantially of such material, for mellowing the tone.

The desirable construction of air sack is one which by inflation expands from the sides of the passage to the center and which can conveniently be constructed by two tube-like portions arranged the one within the other and air sealed at their ends the outer one to substantially fit the passage and the inner portion to expand. In particular the invention provides as a unit applicable to any existing instrument, an appliance comprising, an air sack as aforesaid, an inflation bulb, and a length of tubing connecting the bulb with the air sack, all of india-rubber or other non-metallic flexible material quite flexible and with the air sack conformable to the passage; the bulb for controlling inflation of the air sack to be squeezed by hand either directly or through keys.

The invention in its preferred form is represented by the accompanying drawings, together with a manner of applying it and of using keys for pressure on the hand bulb.

Fig. 1 shows an embodiment of the invention in unit form comprising inflatable air sack shown in longitudinal section, an inflation bulb, and tubing connecting the same.

Fig. 2 is an outer end elevation of the air sack.

Fig. 3 is a transverse section on the dotted lines C. D. Fig. 1.

Fig. 4 is a section on the dotted lines A. B. Fig. 1.

Fig. 5 is a similar section as Fig. 3 but showing the air sack when inflated and how the inner wall expands from the sides to the center in gussets.

Fig. 6 shows a sectional elevation of one way the unit may be applied to the tone arm of a sound reproducing instrument.

Figs. 7, 8 and 9 show in transverse section and in plan an arrangement for key operation of the inflating bulb.

The air sack *a* is formed of two tube-like portions *a*², *a*³ formed of india-rubber or like material disposed the one within the other and air sealed at their ends except at *a*⁴ where said sack is joined up to the air supply tube. The outer end is sealed by doubling the material of the two tubes as at *a*⁵, while the free ends are vulcanized together as at *a*⁶. Between the two ends the two tube-like portions are free of each other, as shown at *a*⁷, providing a space into which air under pressure is forced through the india-rubber tube *c* from the inflation bulb *d* which may be either hand, key, or otherwise operated. Fig. 6 shows how the unit Fig. 1 is applied to the tubular tone arm *e* of an instrument, being threaded through said tone arm, for which purpose the tube may be detachable at *c*² near the bulb *d*. The tube *c* is of any convenient length so that the hearer may sit comfortably in a chair a distance away from the instrument and control the tone in volume or mellow ness as he wills, thereby giving the instrument an additional interest inasmuch as the hearer can display personal musical ability and skill and obtain much more interesting effects than hitherto.

The air sack *a* lies closely within the tone arm fitting the interior and is normally deflated allowing the maximum sound aperture therethrough. By squeezing the bulb *d* the air sack is inflated to further bind it to the bore of the passage in the tone arm and to force the inner tube *a*³ inwardly towards the centre to further close or throttle the passage and in practice the air sack represented expands towards the centre, as repre-

sented by Fig. 5. Dependent upon the pressure on the bulb *d* the effective passage further is closed and again opened. Immediately the pressure of air is relieved expanded portions retreat or move back to normal positions.

The air sack by being made of india-rubber or similar flexible and non-metallic material materially assists in improving the character of the tone, that is to say, it mellows the otherwise metallic tone.

The invention is not limited to the construction of air sack shown; said air sack may be a small bulb similar to the bulb *d* inserted in the tone arm passage and being a loose fit so that sound freely passes it, this bulb being increased in diameter from the hand bulb to throttle the passage and control the effective size thereof in which case said inner bulb would have its position fixed within the tone arm.

Figs. 7, 8 and 9 show how the inflation bulb *d* may be arranged for key operation to give a more sensitive control.

A box *f* is provided within which the power bulb *d* is located between a fixed seating *g* and keys *h*, which latter press against the bulb at *h*² from hand operation of their knob ends *h*³. Contact between the key and the bulb may be by fairly hard india-rubber blocks. Two keys *h* are shown in the arrangement of the drawings, either or both of which can be hand operated, either separately or together. The box may be a part entirely separate from the instrument, or the primary features of it may form part of a special machine cabinet.

Having now described my invention what

I claim and desire to secure by Letters Patent is:—

1. A control device for sound reproducing instruments having a passage beyond the sound box, comprising an air sack of elastic material, having parallel walls one of which is adapted to expand outwardly and the other inwardly, a hand operated bulb used outside the instrument for inflating the air sack and a length of tube connecting the bulb with the air sack, the air sack bulb and tube being formed as a unit applicable to an instrument substantially as described.

2. A control device for use with sound reproducing instrument having a tubular passage positioned beyond the sound box comprising a tubular double walled air sack adapted to be disposed within the passage, a pneumatic bulb used outside the instrument for inflating the air sack, a length of tube connecting the bulb with the air sack and hand operated keys for controlling the sensitive operation of the pneumatic bulb substantially as described.

3. A device to be used with sound reproducing instruments having a tubular passage beyond the sound box, comprising a tubular sack adapted to be inserted into the tubular passage, said sack consisting of outwardly and inwardly expandible coaxial tubular walls, a pneumatic bulb, and a flexible tube connecting said bulb and sack.

In testimony whereof I have hereunto set my hand in presence of a subscribing witness.

ARTHUR EMETT.

Witness:

JOHN P. FUERY.
